F. E. FRENCH.
METALLIC RAILWAY TIE.
APPLICATION FILED, AUG. 23, 1916.

1,213,612.

Patented Jan. 23, 1917.

Inventor

FRANKLIN E. FRENCH

UNITED STATES PATENT OFFICE.

FRANKLIN EDWIN FRENCH, OF PRINCETON, INDIANA, ASSIGNOR OF ONE-HALF TO
OLIVER M. CASE, OF OTWELL, INDIANA.

METALLIC RAILWAY-TIE.

1,213,612.

Specification of Letters Patent. Patented Jan. 23, 1917.

Application filed August 23, 1916. Serial No. 116,498.

To all whom it may concern:

Be it known that I, FRANKLIN E. FRENCH, a citizen of the United States, residing at Princeton, in the county of Gibson and 5 State of Indiana, have invented certain new and useful Improvements in Metallic Railway-Ties, of which the following is a specification, reference being had to the accompanying drawings.

10 This invention comprehends certain new and useful improvements in metallic railway ties, and it has for its primary object a durable and strong construction of tie of this character, the parts of which may be 15 very easily made and readily assembled and properly adjusted according to the gage of track desired, and to securely hold the track rails in place.

A further object of the invention is a tie 20 of this character embodying improved means for holding the track rails in position without the use of spikes or similar fastening devices, the parts being so arranged that both rails may be simultaneously clamped 25 and released when desired and in a very quick and easy manner. And the invention also aims to generally improve devices of this class so as to render them more useful and commercially desirable.

30 With these and other objects in view, as will more fully appear as the description proceeds, the invention consists in certain constructions, arrangements and combinations of the parts that I shall hereinafter 35 more fully describe and claim.

For a full understanding of the invention, reference is to be had to the following description and accompanying drawing, in which—

40 Figure 1 is a top plan view of a railway tie embodying the improvements of this invention, Fig. 2 is a longitudinal sectional view thereof on the line 2—2 of Fig. 1, and Figs. 3 and 4 are transverse sections on the 45 lines 3—3 and 4—4 of Fig. 1, respectively.

Corresponding and like parts are referred to in the following description and designated in all of the views of the accompanying drawing by like reference characters.

50 The body portion A of my improved metallic railway tie is constructed in complementary sections 1 and 2, said sections being hollow, as shown, and preferably of a substantially semicircular shape, although 55 it is to be understood that the invention is

not limited in this regard. The sections 1 and 2 are formed at their ends with transverse webs 3 whereby said ends are closed, and concrete or ordinary ballast may be received within the hollow portions of the sections so as to securely hold it in place. Preferably each section is formed midway of its ends across its bottom with a transverse brace 4, preferably located directly under the rail seat. 60

The sections 1 and 2 of the tie are formed at their adjoining ends with longitudinally extending arms 5 which overlap, as shown, to form a joint in the nature of a scarf joint, the overlapping arms forming continuations of the sections at the sides thereof and each pair of arms being formed with bolt openings 6 to receive bolts 7 or similar fastening devices, each arm being preferably provided with a plurality of these 75 openings 6 whereby the two sections may be adjusted one relative to the other according to the desired gage of the track.

Each section of the tie is formed on its upper surface and intermediate the ends thereof, with a transversely extending undercut shoulder 8 designed to engage the outer base flange of a rail 9 and the sections are formed, contiguous to the shoulders 8, with flat rail supporting surfaces 10, the 85 sides of which are formed with longitudinally extending recesses 11 forming side flanges 12, as clearly illustrated in the drawing.

In connection with the undercut shoulders 90 8, I provide rail engaging members 13 which are in the form of plates, as shown, having their side edges turned downward and inward to form retaining flanges 14 engaging around and under the flanges 12 whereby 95 the rail engaging members or plates 13 are retained and guided for a longitudinal sliding movement upon the ties. Each rail engaging member or plate 13 is formed at its outer end with a projecting lip 15 which is 100 preferably beveled on its under surface, as indicated at 16, for engagement with the inner base flanges of the rails.

The members or plates 13 are formed at their inner ends with preferably integral 105 stem or rods 17 which are mounted in longitudinal alignment with each other, as shown, and provided at their adjoining ends with screw threads for engagement by a turn buckle 19, the screw threads of the re- 110

spective stems or rods 17 being right and left hand threads, as clearly illustrated in the drawing, whereby movement of the turn buckle in one direction will draw the plates or members 13 toward each other out of engagement with the rails 9, and an opposite movement of the turn buckle will force the plates or rail engaging members firmly into engagement with the inner base flanges of the rails, whereby the latter will be firmly held in position in between the beveled lips 15 and the undercut shoulders 8.

If desired, the turn buckle 19 may be provided at its ends with locking nuts 20 and it may be made in two sections bolted together, as at 21, so that an insulating substance may be inserted between the two sections of the turn buckle for the purpose of assisting in insulating the tie.

From the foregoing description in connection with the accompanying drawing, the operation of my improved railway tie will be apparent. In the practical use of the device, after the two sections 1 and 2 of the body portion A of the tie are coupled together, as required, according to the desired gage of the track, the rails 9 are engaged at their outer base flanges with the undercut shoulders 8 and by operating the turn buckle 19 in the required direction, the rail engaging members or plates 13 are moved outwardly upon the ties so that the lips 15 engage with the inner base flange of the rails, and the latter are securely held in position.

Preferably the arms 5 are of a width less than the height of the sections 1 and 2, whereby an open space is provided for the convenient and easy manipulation of the turn buckle 19.

While the accompanying drawing illustrates what I believe to be the preferred embodiment of my invention, it is to be understood that the invention is not limited thereto but that various changes may be made in the construction, arrangements and proportions of the parts without departing from the scope of the invention as claimed.

What is claimed, is:

1. A railway tie of the character described, comprising complementary sections formed at their inner ends with overlapping arms, means for adjustably connecting said arms at different extensions, for the purpose specified, the sections being formed with rail supporting surfaces and at the outer ends thereof with undercut shoulders extending transversely, rail engaging plates slideable upon and retained on said rail supporting

surfaces and formed with lips for engagement with the inner base flanges or rails, and means for moving said lips toward and away from each other.

2. A metallic railway tie consisting of complementary hollow sections closed at their ends and formed intermediate of their ends with cross braces at their bottoms, the sections being further formed at their adjoining ends with overlapping side arms, each formed with a plurality of bolt holes, bolts adapted to extend through said holes whereby the sections may be held together in different adjustments lengthwise of the tie, the sections being formed with rail supporting surfaces, and means for holding the rails on said surfaces.

3. A tie of the character described comprising complementary sections each formed with a transversely extending undercut shoulder designed to engage the outer base flange of a track rail and with a rail supporting surface extending inwardly from said shoulder, the side edges of said rail supporting surfaces being provided with longitudinal recesses forming longitudinally extending flanges, rail engaging plates movable on said rail supporting surfaces and formed with downwardly and inwardly turned side flanges engaging the flanges of said surfaces, the said plates being formed at their inner ends with threaded stems and at their outer ends with beveled lips adapted to engage the inner base flange of the rails, and a turn buckle engaging the threaded stems, as and for the purpose set forth.

4. A tie of the character described, comprising complementary sections formed at one end with longitudinally extending side arms, said side arms being of a width less than the height of the sections, and the arms being arranged in overlapping relation to each other, means for holding said arms connected together, the sections being formed with rail supporting surfaces, rail engaging plates movable upon said surfaces and formed at their adjoining ends with longitudinally extending threaded stems extending over the space between and above said arms, and a turn buckle receivable in said space and engaging said stems, for the purpose specified.

In testimony whereof I hereunto affix my signature in the presence of two witnesses.

FRANKLIN EDWIN FRENCH.
